UNITED STATES PATENT OFFICE.

JAMES S. McCOY, OF BROOKLYN, NEW YORK.

PNEUMATIC TOOL.

SPECIFICATION forming part of Letters Patent No. 323,053, dated July 28, 1885.

Application filed September 1, 1884. (No model.)

To all whom it may concern:

Be it known that I, JAMES S. McCOY, of Brooklyn, in the county of Kings and State of New York, have invented a new and Improved 5 Pneumatic Tool, which invention is fully set forth in the following specification.

This invention consists of a new and improved pneumatic tool for working in stone and for other purposes, wherein a current of 10 air or steam forced into the tool causes a piston or striker to deliver rapid blows upon a rod or bar to the outer end of which the cutting-point is attached, all as hereinafter fully described, and pointed out in the claim.

15 Reference is to be had to the accompanying drawings, forming part of this specification, in which similar letters of reference indicate corresponding parts in all the figures.

Figure 1 is a longitudinal sectional elevation of my new and improved pneumatic tool. 20 Fig. 2 is a front elevation of the piston-chamber, with the outer shell removed to show the air-passages. Fig. 3 is a front elevation of the opposite side of the piston-chamber, and Fig. 4 shows the valve removed.

25 The section A of the main casing of the tool is formed with the air-inlet passage a, exhaust-passage a', and with the piston-chamber b, in which the piston or striker D fits. 30 The lower section, B, of the main casing is screwed to the section A, as shown, and is formed with the countersink c, to receive the flat head or plate d of the tool-carrying rod or spindle C, placed in the section B. The 35 part a' of the section A, which incloses the piston-chamber b, is surrounded by the shell b', and this part a' has three slots or ports, k l m, and also the four passages or ports n n' and o o', Fig. 1, made through it, and upon 40 its outer surface the said part a' is faced off on opposite sides, as shown at p q, Figs. 2 and 3, and is grooved or recessed, as shown at r, s, t, and u.

45 The piston or striker D is made to fit exactly in the chamber b, so as to control the passages and slots above mentioned made in the part a' of section A, and is provided with the transversely-arranged valve e, and is formed with the transverse air-passages h and 50 i, which coincide with the slots k l, with the

transverse passage j, (shown in dotted lines in Fig. 1,) which coincides with the slot m, and with the vertical air-passages f g, (also shown in dotted lines in Fig. 1,) leading, respectively, to the top and bottom of the piston or striker from the chamber in which the valve e is placed.

The valve e is formed with the grooves e' e', arranged so that the valve in its reciprocating movement, caused by the pressure of air 60 entering the ports n and o', alternately opens and closes all the air passages through the piston or striker D.

In operation air, being admitted through the induction-passage a into the passage p, 55 (the striker being in the upper position,) passes through passage t and port n, moving valve e to close passage i and to connect passages m, j, and f, whereby air is admitted above the striker D, and at the same time the 60 passages h, k, and g are connected to allow exhaust from below striker D through passages q and a'. Then the air through passage u and port o' moves valve e to close passage h, to connect passages m, j, and g, to admit 75 air below the striker, and to connect passages f, i, and l, to open the exhaust from above the striker, and so on alternately, thus causing the striker to have a rapid reciprocating movement, causing it to deliver rapid blows 80 upon the plate d of the tool-carrying rod C, which forces the rod C suddenly down in the tube B' against the pressure of the spring h', which, after each blow of the striker, returns the rod C to its original position. 85

The stroke of the piston or striker D upon the plate d acts to force the rod C down, partly by impact of the striker against the plate d and partly by concussion of the air against said plate; hence the effectiveness of the tool 90 is increased by the increased surface obtained by the plate d, and by employing this plate d and the countersink c the upward movement of the rod C and plate, caused by the reaction of the spring h', produces a partial vacuum 95 below the plate d, so that there is very little resistance of air to the downward movement of the plate d.

The tool thus constructed is adapted for drilling rock, dressing and carving marble 100

and other stone, calking boats, chasing brass and silver and other metal, and for various other uses.

Having thus described my invention, I claim
5 as new and desire to secure by Letters Patent—

The combination of induction and eduction ports in the piston-chamber *b*, and striker *D*, controlled by the valve *e* within the striker *D*, and the plate *d* of the tool-bearing rod to

cushion the piston or striker and valve at 10 every point with air so perfectly as to secure the minimum amount of wear in the working parts of the tool.

JAMES S. MCCOY.
